UNITED STATES PATENT OFFICE.

FRANK H. LEHMAN, OF LEBANON, PENNSYLVANIA.

GAME APPARATUS.

1,153,395.

Specification of Letters Patent. Patented Sept. 14, 1915.

Application filed December 21, 1914. Serial No. 878,399.

To all whom it may concern:

Be it known that I, FRANK H. LEHMAN, a citizen of the United States, residing in the city of Lebanon, county of Lebanon, and 5 State of Pennsylvania, have invented certain new and useful Improvements in Game Apparatus, of which the following is a specification.

This invention relates to improvements 10 in game apparatus and more particularly to the type of such apparatus wherein the players score, or move from one station to another, or otherwise progress toward some desired end in accordance with directions resulting from the actuation of an indicating device.

One object of the invention is to provide 15 an indicating device of a unique and novel kind, comprising a vertical upright or post-like member having a flexible pendulous member attached thereto, the latter being adapted to be thrown by the player in such a manner as to twine and untwine about the vertical member, and, according to the deftness and chance of the throw, either to be 20 caught and arrested by means provided on the vertical member for that purpose, or to continue its twining and untwining movement until its momentum has been spent, 25 when it may drop upon a base at the foot of the vertical member. Both the vertical member and the base bear indicia suitable 30 for rewarding skill and judgment on the part of the player, and for otherwise affording opportunity for playing an interesting 35 and entertaining game.

A further object of the invention is to provide, in conjunction with the indicating device, a game board having represented 40 thereon a course of stations for the movement of playing men, such course being arranged to afford amusement to the players and to arouse a spirit of friendly rivalry 45 between them.

A further object of the invention is to provide a game made of few parts which may be readily and easily assembled, and which, when knocked down, may be completely contained in a compact box, all of 50 said parts being of simple construction and designed for economical manufacture.

With the above and other objects in view the invention consists in the novel construction, arrangement and combination of parts

as hereinafter more fully described, illustrated in the drawings, and pointed out in the appended claims.

In the accompanying drawing Figure 1 is a perspective view of my improved game showing the parts thereof as the same appear when completely assembled. Fig. 2 is a cross-section of the base box taken centrally on line $y-y$ of Fig. 1. Fig. 3 is a front elevational view of the vertical member; and Fig. 4 a side view thereof.

Similar letters and numerals of reference designate corresponding parts in all of the views of the drawings, referring to which—

P represents a vertical member in the form of an upright or post which may be 70 made in a variety of different shapes. In the present instance I prefer to construct this member in the shape of a fan, the same having a lower and substantially cylindrical portion or shank 1, and an upper flat sheet 75 portion 2, the latter being made of some comparatively thin and rigid sheet material, such as card board, bone, celluloid, sheet metal, glass or wood. The portion 2 is firmly secured to the shank in any suitable 80 and obvious manner, as for instance by seating the same in a longitudinal slot cut in the upper end of the shank and applying glue or inserting tacks transversely in the shank.

For playing the game it is requisite, as 85 will hereinafter more clearly appear, that the member P be erected and firmly supported in a vertical position, and for so positioning and securing said member any suitable means may be adopted. I prefer, however, to employ for this purpose a flat base 90 having a socket centrally formed therein and adapted to receive the lower part of the shank 1, and I further prefer to form this base in the nature of an approximately rectangular box such as B, having a lower or body part A¹ and a lid A. A block C arranged in the center of the box is formed with a socket 14 adapted to receive the lower end 11 of the shank, and a perforation 12 of appropriate size and shape in the lid of the box permits the insertion of the shank into the socket. The lower end 11 of the shank and the bore of the socket are slightly tapered as shown, whereby a light pressure 100 on the vertical member will be sufficient to seat it securely on the base.

The upper portion 2 of the vertical mem-

ber is preferably of greater length than width, and of greater width in the center than at the ends, the lateral edges converging toward either end and being substantially 5 arcuate in contour. Near the top of the portion 2 is attached a pendulous member 10 consisting of a flexible cord, chain or band 8, which may be wholly or in part elastic, having a bob 9 secured to the end thereof. This bob constitutes the indicator and is preferably made of some thin flat material having the requisite weight such as metal or glass, and is provided with an indicating point as 9¹. In playing the game, 10 the bob is taken up by the player and thrown horizontally in such a manner that the member 10 will repeatedly twine and untwine about the vertical member, normally continuing this movement in the nature of a 15 pendulum until its momentum has been exhausted when it will drop upon the lid A of the box. As will be understood, this would be the invariable movement of the pendulous member when thrown about the 20 member P, were the path of the former free from interruption or interference. However, for the purpose of varying the movement, rendering the result of any given throw to some degree uncertain, and thus 25 adding an element of novel interest to the operation of the device, while affording the player an opportunity for the exercise of skill and judgment, I provide means whereby the member 10 may be arrested, when the 30 35 bob is so thrown as to bring said member into coöperation with such means. These means may take on a number of different forms, designs and shapes. In the drawings I illustrate an embodiment of my invention 40 wherein these means are shown as consisting of perforations as 4 and 5 in the portion 2 of the vertical member, through which the bob 9 may pass when so thrown as to coincide therewith, and wherein the 45 bob may be caught in the manner indicated by the dotted lines. I likewise show additional means for the same purpose consisting of marginal indentures 6 and 7 cut in the lateral edges of the portion 2. It will 50 be clear that when the bob is thrown so as to bring the cord 8 into coincidence with either of these indentures, the same will be caught therein and the movement of the member 10 thus again arrested. Adjacent 55 these means for catching the bob and the cord on the member P are marked numerical indicia or arbitrary values as for example 4, 5, 2, 2, and on the upper surface of the box lid or base is represented a circle m 60 divided into a plurality of segments as i, o, g, j, h, and k, said segments being alternately plain or in the common color of the base, and alternately of a series of different colors such for example as red, blue and green. Within the outer circle m is a 65

smaller circle n concentric therewith, and likewise in the common color of the base.

In connection with the indicating device as thus described, I employ a game board, imprinted with a course of suitably spaced and colored stations for the movement of playing men in accordance with directions denoted by the various indicia. Preferably I utilize the base, or, as in the present instance, the lid A of the base box for this purpose, marking thereon a continuous course as e of uniformly patterned spaces or stations as e¹, adjacent to, and following the marginal sides thereof. The course as shown is intended for either two or four 70 players, opposing players moving their respective men in opposite directions, so that the initial or starting point of one player becomes the terminal or objective point of his opponent. These initial and terminal points are represented by the opposed stations e and e¹, preferably located centrally on one side of the board, and having an enclosed space marked "Goal" between them. 75 On the opposite side of the board, intermediate the stations e and e¹ in the course is an interrupting space d marked in some appropriate and significant manner, as in this case at d¹ by the word "Exchange." The stations e¹ of the course are arranged in successive sets, the stations of each set being equal in number to the colored segments, as i, g and h, of the circle m, and the individual members of each set are colored successively to correspond with the different 80 respective colors of the successive colored segments. Disks, such as s, shown on the right hand starting station e may be used 85 for playing men.

The rules for playing the game will, of course, be purely arbitrary, and may be modified to a great extent; but by way of suggesting a preferred mode of procedure and play, it may be observed that the players will play in alternation, and at the out-start opposing players will place their respective men on the opposite starting stations e and e¹ respectively. Then the first player takes up the bob 9 and throws it 90 around the vertical member P. Either the bob will now be caught in one of the perforations 4, 5, or the cord 8 in one of the indentures 6, 7, or, after the pendulous member has twined and untwined several times about the vertical member, the bob will 95 alight on one of the segments i, o, g, j, h, k of the board. Should the throw result in the bob being caught in one of the perforations or indentures, the player, assuming him to control the man on the right hand starting station, advances said man along the course to the right such number of stations as the numerical indication marked adjacent said perforation or indenture may 100 direct. The player, likewise, having thus 105

effected one of the more difficult throws of the game, becomes entitled to another turn. Should his throw now result in the bob dropping on the board in the position shown 5 in the drawing with the point thereof on the red segment *i*, the player advances along the course as before to the next station bearing the color of this segment, receiving however for such throw no additional turn. The opposing player then throws the bob, advancing 10 his man, however to the left along the course. Thus whenever either the bob or the cord happens to catch on the vertical member, the player making the throw advances 15 in accordance with the numerical indicia and is privileged to take another turn, and when the bob alights on the board with its point on one of the colored segments, the player advances to the next station bearing 20 the color struck, without however receiving an additional turn, and so on. Should the bob drop with its point on one of the plain segments *o*, *j*, *k*, the player goes back to the nearest station bearing the color of the 25 colored segment nearest the point of the bob, and in case the point of the bob falls within the small circle *n*, the player goes back to the starting point. The player first arriving 30 at the space *d* and making a throw entitling him to advance across the same, may, instead of so doing, should he desire, call out a word indicative of a preference such for example as "exchange," and thereupon may exchange both positions and men with his 35 opponent, both players thereafter continuing along the course in their respective directions as before. The player first reaching the point marked "Goal," wins the game, but this point having no particular 40 color can only be reached from one of the final stations of the course by a throw giving a numerical indication, which latter, as is understood can only be attained when the pendulous member is caught on the vertical 45 member.

I have noticed that when the socket block *C* is securely affixed to the base or box *B*, the bob upon falling on the board has a tendency to drop repeatedly on certain segments of the circle *m* to the exclusion of others and thus render the chances of players throwing from opposite sides of the vertical member disproportionate. This 50 tendency may be overcome by disposing the socket block *C* loosely in the box or mounting the same on a pivot (not shown) whereby it may be free to revolve in a horizontal plane, thus enabling the vertical member to be rotated on its vertical axis in response to 55 the torsional stress of the pendulous member when thrown about the same. This, therefore, together with many other conceivable modifications of both the indicating device and the playing board, I regard as 60 falling within the spirit of my invention.

Having thus described my invention, I claim as new and desire to secure by Letters Patent:—

1. In game apparatus, a vertically supported member of thin sheet material, a flexible pendulous member attached thereto and adapted to be thrown to twine about the same, and means formed integral with the vertical member whereby said pendulous member may be caught when so thrown. 75

2. In game apparatus, a vertically supported member having an upper portion of thin sheet material, a flexible pendulous member attached to said vertical member and adapted to be thrown to twine about the same, and means formed integral with said upper portion of said vertical member, whereby said pendulous member may be caught when so thrown. 80

3. In game apparatus, a vertically supported member of thin sheet material, a flexible pendulous member attached thereto and adapted to be thrown to twine about the same, and means provided on the vertical member whereby said pendulous member may be caught when so thrown, said means including perforations in said vertical member. 85

4. In game apparatus, a vertically supported member of thin sheet material, a flexible pendulous member attached thereto and adapted to be thrown to twine about the same, and means provided on said vertical member whereby said pendulous member may be caught when so thrown, said means including indentures cut in the marginal sides of said vertical member. 90

5. In game apparatus, a vertical member supported on a base, a flexible pendulous member attached to said vertical member and adapted to be thrown to twine about the same, said pendulous member consisting of a cord or ligature having a flat sided bob secured to the end thereof. 105

6. In game apparatus, a base having a continuous surface, a vertical member centrally erected of said base, a flexible pendulous member attached to said vertical member and adapted to be thrown so as to twine about the same and to alight on said base, said base being divided into a plurality of sections having predetermined designations. 110

7. In a game, the combination with an indicating device of a substantially rectangular game board having represented thereon a plurality of successive stations forming a course for the travel of playing men, said course lying adjacent the marginal sides of the board and following the same, and said course being relatively narrow and designed for the movement of said playing men in opposite directions thereon, initial and terminal stations in said course arranged opposite each other at a central point on one side of the board, said stations having 115 120 125 130

an intervening field space between them with a station marked "Goal" in line with said course but distinct therefrom located adjacent said initial and terminal stations in said field space, and another station marked "Exchange," likewise in line with said course and at a point therein intermediate said initial and terminal stations, but

located on the side of the board opposite said stations.

In testimony whereof I have affixed my signature in the presence of two witnesses.

FRANK H. LEHMAN.
